UNITED STATES PATENT OFFICE.

BENJAMIN LOUIS TOQUET, OF WESTPORT, CONNECTICUT.

OILING DEVICE.

Application filed October 6, 1924. Serial No. 741,972.

To all whom it may concern:

Be it known that BENJAMIN LOUIS TOQUET, a citizen of the United States, and resident of Westport, in the county of Fairfield and State of Connecticut, has invented certain new and useful Improvements in Oiling Devices, of which the following is a specification.

This invention relates to oiling devices for internal combustion motors, and more especially to those auxiliary oiling devices for Ford motors which deliver oil to the crank case through the breather tube. Heretofore, such auxiliary devices have delivered oil directly into a breather tube at or near its inlet with the result that a part of the oil has been blown out of the tube by blasts of air caused by the action of the motor pistons, to be spattered over the outside of the motor. This blowing out has been lessened to some extent by the provision of gauze screen to cover the tubes, but this protection at its best is inadequate.

The present invention has for one of its objects to provide a novel and improved oiling device of the character mentioned adapted to deliver oil at a point well within a breather tube and far enough below the breather tube inlet to preclude the possibility of the blowing out of said inlet of any of the oil.

Another object of the invention is to provide an oiling device as just stated wherein the flow of oil through the device can be visible.

And yet another and more specific object of the invention is to provide an oiling device as stated in the two paragraphs just preceding, wherein provision is made for creating a head of oil at the location where the oil enters a breather tube from the improved oiling device, the head of oil being adapted to form a seal in an open conduit of the device, which conduit is designed to allow the flow of oil to be visible past the inlet of said breather tube, whereby the blowing of air upwardly through said conduit is prevented.

With the above and other objects in view, the invention comprises the construction, arrangement and combination of parts as now to be fully described and as hereinafter to be specifically claimed; it being understood that the disclosure herein is merely illustrative and meant in no way in a limiting sense, changes in details of construction and

arrangement of parts being permissible so long as within the spirit of the invention and the scope of the appended claims.

In the accompanying drawing forming a part of this specification,

Fig. 1 is a side elevational view of an automobile engine having an oiling device in which the features of the invention are incorporated;

Fig. 2 is a vertical, longitudinal, central sectional view, on an enlarged scale, of the improved oiling device, showing the same applied to a breather tube;

Fig. 3 is a top plan view of the oiling device and breather tube of Fig. 2, with breather tube cap or cover removed; and

Fig. 4 is a sectional view, corresponding with the showing of Fig. 2, of an oiling device of modified construction.

In Figs. 1, 2 and 3 of the drawing I have disclosed a device having provision (a) for delivering oil to a point well within a breather tube to preclude the possibility of the blowing of oil out of said breather tube; (b) for rendering visible the flow of oil through the device; and (c) for creating a head of oil at the location where the oil enters the breather tube from the oiling device, to form a seal in an open conduit of the device whereby the blowing of oil upwardly through the conduit of the device is prevented. In Fig. 4 of the drawing I have disclosed a novel and modified arrangement of conduit, which is not open to the inlet of the breather tube or an extension piece therein, for similarly delivering oil well within a breather tube and far enough away from its inlet to prevent the blowing of oil out of said breather tube, the modified arrangement ordinarily not providing for visibility of flow of oil through the conduit, but the flow being visible when said conduit is a transparent member or is provided with a sight glass.

With respect to Figs. 1 to 3 of the drawing, 10 denotes an automobile engine, 11 the crank case thereof, 12 a hollow shell or the like situated in usual or preferred manner above the fly wheel (not shown) for receiving oil from the transmission case as the fly wheel rotates, and 13 denotes an oil feed pipe leading from the shell 12 toward the breather tube 14.

Of the improved oiling device, 15 is a generally cylindrical extension piece adapted to fit into the breather tube as represented

at 16, and 17 is an oil conduit, preferably arranged vertically in the extension piece and breather tube, which is held in place in the extension piece 15 by a separator or spider 18 provided with openings 19 for the free passage of air. The usual cap or cover 20 for the breather tube is adapted to fit upon the upper end or inlet 21 of the extension piece.

15 The oil feed pipe 13 passes through openings 22 and 23 in the extension piece 15 and conduit 17, respectively, to deliver oil at 24 within the conduit 17, the location 24 being, as shown, not far from the upper end or 15 inlet 21 of the extension piece.

20 The conduit 17 is of somewhat greater diameter than is the feed pipe 13, and the delivery end of the feed pipe is, naturally, visible past the inlet of the breather tube 23 when the cap or cover of the tube is removed. The lower end or delivery end 25 of the conduit 17 is preferably reduced in area, for two purposes: First, to collect the oil into a solid stream before its delivery to 25 the breather tube at the location well within said breather tube so that blasts of air, caused by alternate pressure and vacuum in the crank case due to the action of the motor pistons, through the breather tube and 30 around the conduit 17 will not be sufficiently powerful to blow any of the oil out of the breather tube inlet; and, second, to cause a partial stoppage of flow of oil through the conduit 17 and thus create a slight head of oil at the delivery end of the conduit to 35 form an oil seal and effectively prevent all portions of said blasts of air from blowing upwardly through said conduit.

40 With respect to Fig. 4, numeral 14' denotes the breather tube, and 20' represents the cap or cover thereof. The oil feed pipe 13' passes through an opening in a bushing 26 threaded in the breather tube as at 27, not far from the breather tube inlet. In 45 the present form of the invention, the extension piece is omitted, and the oil feed pipe has a right-angle bend 28 situated desirably near the transverse center of the breather tube, to provide a conduit 17' having 50 a delivery end 25' situated with respect to the breather tube as the delivery end 25 of the conduit 17 is situated. The flow of oil through the conduit 17' of the feed pipe 13' will be in a solid stream, ordinarily, and 55 oil delivered to the breather tube from the conduit 17', well within the tube, will not be blown out of the breather tube inlet.

60 Ordinarily, the oiling device of Fig. 4 will not be provided with an arrangement 60 whereby the oil flowing through the conduit 17' can be visible, but clearly, this flow of

oil could be visible were the conduit 17' a transparent member, or were it provided with a sight glass (not shown).

65 It will be evident that the pipe 13' with conduit 17' could be associated with an extension piece in the breather tube, such as the extension piece 15, instead of with the breather tube itself.

Having thus fully described the invention, what I claim as new and desire to 70 secure by Letters Patent is:

1. In combination with a crank case and a breather tube adapted to allow the delivery of oil to said crank case, an extension 75 piece adapted to fit said breather tube, a conduit located in said extension piece and having a delivery end situated well within said breather tube at considerable distance from the inlet of said tube, and an oil feed 80 pipe including a delivery end entering said conduit.

2. In combination with a crank case and a breather tube adapted to allow the delivery of oil to said crank case, an extension 85 piece adapted to fit said breather tube, a conduit located in said extension piece and having a delivery end of reduced area situated well within said breather tube at considerable distance from the inlet of said 90 tube, and an oil feed pipe including a delivery end entering said conduit.

3. In combination with a crank case and a breather tube adapted to allow the delivery of oil to said crank case, an extension 95 piece adapted to fit said breather tube, a conduit located in said extension piece and having a delivery end situated well within said breather tube at considerable distance from the inlet of said tube, and an oil feed 100 pipe passing through said extension piece and including a delivery end entering said conduit, whereby oil passing from said delivery end can be visible past the inlet of said breather tube.

105 4. In combination with a crank case and a breather tube adapted to allow the delivery of oil to said crank case, an extension piece adapted to fit said breather tube, a conduit located in said extension piece and having a delivery end situated well within said breather tube at considerable distance from the inlet of said tube, a separator insuring the position of the conduit in the extension piece, and an oil feed pipe fitted 110 in the extension piece and entering the conduit.

115 Signed at Westport, in the county of Fairfield and State of Connecticut, this first day of October, A. D. 1924.

BENJAMIN LOUIS TOQUET.
